UNITED STATES PATENT OFFICE.

JOHN F. GODFREY, OF ELKHART, INDIANA.

SELF-DUMPING CONVEYING-BUCKET.

1,306,758.

Specification of Letters Patent. Patented June 17, 1919.

Application filed May 31, 1918. Serial No. 237,334.

To all whom it may concern:

Be it known that I, JOHN F. GODFREY, a citizen of the United States, residing in the city of Elkhart, county of Elkhart, and State of Indiana, have invented certain new and useful Improvements in Self-Dumping Conveying-Buckets, of which the following is a specification.

This invention relates to improvements in self dumping buckets and especially to self dumping buckets used for conveying coal, and like materials, from one place to another.

An object of my invention is the production of a self dumping bucket provided with bottom dumping doors having improved trip mechanism for automatically dumping the bucket. Other objects are mentioned and described herein.

The preferred embodiment of my invention is well illustrated in the accompanying drawing in which Figure 1 is a side elevation of a bucket to which my invention is applied; Fig. 2 is a section in elevation through the bucket shown in Fig. 1; Fig. 3 is an enlarged fragment of the bucket bottom showing one door and the trip mechanism in operative position; and Fig. 4 is a view showing the bucket operated by an overhead carrier system having a fixed trip member.

Similar numerals of reference indicate similar members and parts of members throughout the several views on the drawing.

On the drawing, the numeral 1 indicates a bucket body open at the top and bottom thereof, said bottom being normally closed by a pair of co-operating dumping doors 2 and 3, respectively, which are hinged to the bucket at 4 and 5, respectively, and adapted to swing downward for dumping the bucket contents.

Numerals 6 and 7 indicate coil springs anchored within and to the bucket at 8 and 9, respectively, and at 10 and 11, respectively, to the doors 2 and 3, said springs being adapted to maintain a closure of said doors and to effect a closure thereof after the bucket has been dumped. Numeral 12 indicates a carrier bar rigidly fastened to the under side of the door 2 at 13, 13 and extending transversely of the bucket bottom and beneath and across the door 3, said bar being preferably of channel formation opening downward and adapted to support and carry the doors 2 and 3 when the outer end

14 of said bar is disengageably supported, as hereinafter described.

Numerals 15 indicates a latch or carrier lever pivotally mounted on the bucket exterior at 16 to swing in a vertical plane, said lever being provided with a ledge or abutment section 17 adapted to project beneath the carrier bar end 14 for supporting the bar 12, and thereby said doors 2 and 3, said lever being provided also with an extension arm 18 which is outwardly pressed by the spring 19 secured to the bucket exterior at 20 for yieldingly projecting the lower end of the lever 15 and ledge 17 inward and maintaining the latter beneath the bar end 14. The lower end of the lever 15 is beveled at 21 for engagement by the bar end 14 when the door 2 and said bar are swung upward by the spring 6 to facilitate engagement of the ledge 17 by the bar end 14.

Numerals 22 indicates a latch trip member carried by the bar 12, one end whereof is hinged to the lower end of a link 23 at 24, the upper end of said link being pivotally mounted in the channeled bar 12 at 25, said hinge 24 being substantially spaced beneath said bar member. The trip member 22 is preferably of channel formation the flanges whereof are cut away at 26 adjacent the outer end thereof, thereby forming a hook 27 thereon, said space 26 being engaged by a carrier pin 28 fixed transversely of and in the bar 12 adjacent the bar outer end 14. Numeral 29 indicates a spring anchored in the bar 12 at 30 and in the trip member 22 at 31, being adapted to retract the trip hook 27 against the stop pin 28 to enable clearance between it and the latch ledge 17 when the bar end 14 engages the beveled latch face 21 on its upward swing. The stop pin 28 is adapted also to support the trip member 22 and to confine its end within the channel of the bar 12, the hook 27 whereof is normally disposed adjacent the latch ledge 17. Numeral 32 indicates a bucket bail applied thereto in any suitable form and manner.

In operation, the descent of the loaded bucket projects the trip member hinge 24 upward by contact with the ground or a pile of material already deposited, thereby projecting the trip hook 27 outward against the lower end of the latch lever 15 adjacent the ledge 17, whereby said ledge is forced outward from beneath the bar end 14. Thereupon, the weight of the bucket con-

tents forces open both doors 2 and 3 and the bucket is emptied. In Fig. 4 the bucket is shown as a conveyer bucket supported by a movable carrier member 33 mounted upon 5 a carrier cable 34, upon which said carrier member is adapted to be drawn back and forth and to which, a depending trip member 35 is fixed, said trip member being adapted to throw the latch lever 15 for 10 dumping the bucket, as described, when said trip is engaged by the latch extension 18 while the bucket is in motion.

I claim:

1. The combination with a bucket of the 15 class described provided with a pair of hinged bottom dumping doors, of a carrier bar member mounted upon one of said doors and projecting therefrom beneath and across the other door; a movable spring 20 pressed latch member engaging beneath said bar for supporting same and said doors; and a movable trip member mounted upon said carrier bar and adapted to actuate said latch member upon the descent of the bucket, 25 whereby said latch is disengaged from beneath said carrier bar.

2. The combination with a bucket provided with a pair of hinged bottom dumping doors, of a carrier bar member mounted 30 upon one of said doors and projecting therefrom beneath and across the other door; a movable spring pressed latch member engaging beneath said bar and adapted to support same and said doors; a movable 35 spring retracted trip member carried by one of said doors and adapted to actuate said latch member upon the descent of the bucket, whereby said latch is disengaged from beneath said carrier bar; and a stop 40 member for limiting the retracted movement of the trip member.

3. In a bucket of the class described, a hinged bottom dumping door carried by the bucket; a carrier bar mounted upon said 45 door and extending across the bucket bottom; an oscillatory spring pressed carrier lever mounted upon the bucket and engaging beneath said carrier bar for supporting same and thereby said door; a movable 50 spring retracted trip member carried by said

door and adapted to actuate said lever upon the descent of the bucket, whereby said lever is disengaged from beneath said carrier bar; and a stop member for limiting the retracted movement of the trip member. 55

4. In a bucket having a hinged bottom dumping door, a carrier bar mounted upon said door and extending across the bucket bottom; a movable spring pressed bar carrier member mounted upon the bucket and 60 provided with a ledge adapted to normally engage beneath said bar for supporting same and thereby said door; a trip supporting member mounted upon said carrier bar adjacent its outer end; a movable spring retracted 65 trip member having one end thereof arranged adjacent said bar carrier member and carried by said trip support member, the other end thereof being otherwise carried, said trip member being adapted to 70 actuate said bar carrier and thereby its ledge from beneath said bar upon the descent of the bucket, whereby said door is free to open; and means for limiting the retracted movement of the trip member. 75

5. In a bucket having a pair of hinged bottom dumping doors, a bar mounted upon one of the doors and extending therefrom beneath and across the other door; an oscillatory spring pressed carrier lever mounted upon the bucket and engaging beneath said bar and adapted to support same and thereby said doors; a trip supporting member mounted upon said bar adjacent its outer end; a movable spring retracted trip 80 member having one end thereof hinged to a link which is pivoted in said bar member, the other end of said trip member being carried by said supporting member and arranged adjacent said carrier lever, said 85 trip member being adapted to oscillate said carrier lever upon the descent of the bucket, whereby said lever is disengaged from beneath said bar; and means for limiting the retracted movement of the trip member. 90

In testimony whereof I have hereunto affixed my signature this 27th day of May, 1918.

JOHN F. GODFREY.
